PRECISION GRINDING MACHINE

Jacob Decker and Bernard A. Kearns, Cincinnati, Ohio, assignors to The Cincinnati Milling Machine Co., Cincinnati, Ohio, a corporation of Ohio

Application March 31, 1951, Serial No. 218,568

27 Claims. (Cl. 51—165)

1

This invention relates to improvements in grinding machines and has particular reference to precision machines which are intended for high production operation in the continuous production of similar parts. It is desirable that such machines be capable of utilization for either infeed grinding in which there is a direct relative movement of the work and grinding wheel for effecting desired stock removal or alternatively for traverse grinding in which the work and grinding wheel are given a relative axial or traversing movement with intermittent advance for determination of stock removal.

As respects either type of operation it is conventional that there be a relative retraction between the work holding mechanism and the grinding wheel for introduction and removal of work pieces and in either type of grinding the wheel is subject to decrease in effective diameter or size, both on account of wear and the necessity for intermittent truing to maintain its proper shape and free cutting characteristics.

In such high production machines it is essential for maximum production purposes that the time of the grinding cycle or cycle of operations be held at a minimum. In accomplishment of this it is desirable that the parts be relatively shifted in a direction one toward another as rapidly as possible and that if a fast grinding feed is employed the change should be made from rapid advance to the fast feed automatically at the time of engagement of the operative surface of the grinding wheel with the work, and that proper change from fast to final finish grinding speed likewise be automatically effected at the proper point in the grinding cycle, with controlled rapid separation of the parts when the work is ground to size. If a relative retracting movement of constant amplitude is effected between the work axis and the grinding wheel axis, there will be a time loss in the cycle due to the necessary increase in period of feed required to make up the necessary distance due to wheel wear or stock removal by truing. While this can be compensated for by successive manual adjustments, this requires the constant attention of and is dependent on the judgment of the operator.

One of the principal objects of the present invention therefore is the provision of a machine adapted for either infeed or traverse grinding which will automatically minimize the time lost in feeding on account of such wear and will, therefore, by decrease of the time of operating cycle, increase the maximum potential production output of the machine.

2

A further object of the invention is the provision of an automatic compensating mechanism effective to maintain the distance of retraction of the operative surface of the grinding wheel with respect to the support determined axis of the work piece substantially constant irrespective of wear of the grinding wheel.

A further objective of the invention is the provision of an improved cycle control mechanism for production grinding machines which will minimize the time factor as respects the individual grinding cycle.

An additional object of the present invention is the provision of means under control of a work sizing or gaging mechanism variably to determine the amount of relative retraction of the work and grinding wheel.

Another object of the present invention is the provision in connection with a dual feed rate production grinding machine of automatic means for effecting reduction or change in said feed rates at a point having prescribed relation to the operative surface of the cutting element.

An additional object of the invention is the provision of improved wheel wear compensating means which shall be equally utilizable and effective whether the machine is being employed for infeed or for traverse grinding operations.

Other objects and advantages of the present invention should be readily apparent by reference to the following specification, considered in conjunction with the accompanying drawings forming a part thereof, and it is to be understood that any modifications may be made in the exact structural details there shown and described, within the scope of the appended claims, without departing from or exceeding the spirit of the invention.

Figure 1 is a front elevation of a grinding machine embodying the present invention.

Figure 2 is an expanded sectional view on the line 2—2 of Figure 1.

Figure 3 is a detail elevational view of the compensatory mechanism and associated parts.

Figure 4 is a fragmentary elevation of the relatively adjustable dial and indicator elements.

Figure 5 is the diagrammatic view of one form of hydraulic circuit for effecting and controlling the operation of the machine shown in Figure 1.

Figure 6 is a diagrammatic view illustrating the structural relationship and functioning of the electrical control mechanism.

In the drawings the numeral 15 designates the bed of a grinding machine having translatablely mounted thereon for longitudinal traverse the

table unit 16 bearing the suitably driven headstock 17 and the tailstock 18, providing the centers 19 and 20 respectively for determination of the axis of rotation of the work piece 21.

Additionally, slidably supported by the bed 15 is a wheel head slide 22 bearing the grinding wheel 23. This slide is movable toward and away from the work piece position determined by the headstock and tailstock centers 19 and 20.

Suitably mounted on or formed as a part of the bed 15 is the cylinder block 23' having a first cylinder or chamber 24 in which is movable piston 25 coupled by rod 26 with depending portion 27 of the wheel head slide 22. The block 23' is further provided with an additional cylinder or chamber 28 containing piston 29 having the piston rod 30 extending forwardly therefrom and formed with the screw thread portion 31 engaged in nut portion 32 of member 27. The forward end of rod 30 is splined for relative axial sliding movement with respect to sleeve 33 carried by the stud shaft 34 suitably journaled in the bed 15 and bearing the drive gear 35. It will thus be evident that reciprocation of pistons 25 and 29 will effect a forward and rearward or advancing and retracting movement of the wheel head slide 22 while rotation of gear 35 and thus of screw 31 will vary the effective position of the wheel head for a given amount of movement of the piston 29.

The drive gear 35 is in mesh with pinion 36 on shaft 37 which is manually actuatable as by the pilot wheel assembly 38. This pilot wheel assembly includes a sleeve portion 39 providing a bearing 40 for the friction clutch unit 41. The unit 41 is contained between flange 42 and gear 43, the latter being secured as a closure for the bearing 40 in opposition to flange 42, being retained in place as by the screws 44. The unit 41 includes a body portion having sockets or recesses at 45 to receive springs 46 outwardly urging the friction plate 47 against gear 43. It will thus be seen that the unit 41 is mounted for rotation on the bearing 40 but frictionally engages respectively the flange 42 and gear 43 for rotative movement therewith. The unit 41 is further provided with the peripheral gear section 48 having meshing therewith gear 49 having a hub 50 journaled on the bearing sleeve 51 carried by the bed unit 15. A second gear 52 has a sleeve hub 53 journaled on the left hand portion of the hub 50 so that the gear 52 is rotatably mounted in juxtaposition to the gear 49 and correspondingly meshing with the gear 48. These gears together constitute a compensator unit.

The stud 51 has a tapered or clutch portion 54 adapted for interfitting engagement with the internal clutch face 55 of the sleeve 50 and a central aperture or bore 56 receiving the spring 57 reacting at one end on plug 58 and the opposite end on plunger 59, forcing the latter outward. This plunger reacts against the threaded plug 60 of control button 61 threaded into the left hand or forward end of sleeve 50 so that the spring reaction tends to retain gears 49 and 52 in a forward position, jointly meshing with the gear 48.

When it is desired to effect relative adjustment of the members 53 and 49 the button 61 may be pushed inwardly to move gear 49 out of mesh with gear 48 when the former may be given a relative rotational movement with respect to the gear 52, or alternatively slight additional movement will cause interengagement of

the clutch faces 54 and 55 locking the member 50 against rotation so that relative face adjustment between the gears 49 and 52 may be effected by manual rotation of the gear 48 due to continued meshing engagement of the gear 52 therewith.

By reference to the drawings it will be evident that the cyclic relative movements of work support and grinding wheel support, in the present instance indicated as a movement of the grinding wheel head or slide, are hydraulically effected, the basic hydraulic circuit being particularly illustrated in Figure 5 while the controls for said cyclic and other movements of the machine are primarily electrical as indicated in the control circuit diagram, Figure 6.

Considering first the hydraulic power actuators, there is provided, suitably positioned as in the bed 15, the hydraulic reservoir 62 into which extends the intake 63 of pump 64 discharging into the pressure supply line 65. The pressure in the line and volumetric supply is controlled by relief valve 66 having return conduit 67 returning the excess discharge of pump 64 to reservoir 62, while a low pressure or return conduit system 68 conducts the hydraulic medium back to the reservoir by way of the low pressure valve and filter unit 69.

In Figure 5 the hydraulic circuit control mechanisms have been indicated in the stop position and with the selector valve S in the manual control position. For effecting forward and reverse feeding, as distinguished from the rapid advance or retraction effectable through the piston mechanisms 23' and 29, there has been provided a hydraulic motor 70 preferably of the rotary type having a drive gear 71 in constant mesh with gear 72 on worm shaft 73 carrying worm 74, driving the worm gear 75 on shaft 76. Splined and slidably on the shaft 76 is the reversing gear coupler 77 having a first gear 78 movable into direct intermeshing engagement with gear 35 on shaft 34 for effecting rotation of screw 31 in a direction to feed the wheel head 22 forward to cause engagement of the grinding wheel 23 with the work piece 21.

The coupler has a second gear 79 alternatively engageable with gear 43 as indicated in Figure 2. Unidirectional drive of the coupler in transmitting motion to gear 43 will cause a feed back drive through pinion 36, causing rotation of gear 35 and thus screw 31 in the opposite direction for retraction of the wheel head 22. The gears 78 and 79 are sufficiently spaced to be shiftable into an intermediate or non-engaging position as indicated in Figure 5. This centralized position is effected by the shifter 80 mounted on piston rod 81 supported by the centralizing bushings 82 and 82' having enlarged ends fitting respectively in the cylinders 83 and 84. If equal pressures exist in the cylinders 83 and 84, the centralizing bushings 82 and 82' will maintain the coupler 77 in the position illustrated. If, however, pressure be maintained in either of these cylinders 65 while the opposite cylinder is connected to reservoir or lower pressure, the piston rod and centralizing bushing will move under the influence of the higher pressure to one side or the other, alternatively meshing either 35-78 or 43-79 for transmitting rotation from motor 70 to screw 31.

Such a centralized position, dissociating the power motor drive from the screw 31, leaving same solely under manually control has been indicated in Figure 5 where the selector lever 85 has been indicated in the manual position and

the various portings of the selector valve have been shown in the sections AA, BB, CC, DD, and EE. As there indicated, pressure conduit 65 is connected by way of valve section BB and conduit 86 to chamber 83. Similarly, pressure conduit 65 is connected through valve section CC and conduit 87 to pressure chamber 84.

Alternatively, when valve 85 is moved counterclockwise to the "power position" conduit 86 will be connected through valve section EE to 10 conduit 88, conduit 87 to 89 while the valve portions BB and CC having been moved through 90 degrees will be in a blocking position as respects line 65. At this time valve 90 is held in raised position by spring 91, pressure 15 conduit 65 is connected by cannelure 92 of valve 90 with 89, while 88 is connected by cannelure 93 of valve 90 with the low pressure or return conduit 68 so that the couplet 11 will move to the left and 18 will be meshed with 35 20 to effect retraction of the wheel head upon energization of motor 70. Valve 90 is under control of solenoid D which, when energized, reacts through linkage 94 to depress the valve, coupling pressure conduit 65 by way of cannelure 25 93 with line 88 while shutting off flow into 68. At the same time pressure is disconnected from cannelure 92 and 89 is coupled with 68. This establishes a reversal of pressure conditions, namely, higher pressure in chamber 83 and lower 30 pressure in the chamber 84, moving gear 19 to the right hand position indicated in Figure 2 for reverse actuation of the feed screw. Initiation of a grinding cycle for either infeed or transverse purposes is controlled by the handle 35 T of the start-stop valve 95, the pressure conduit 65 being centrally connected to this valve. Movement of the valve toward the left serves to couple pressure conduit 65 by way of cannelure 96 with pressure switch 97 momentarily energizing control relay CR1 which is then locked in energized condition by CR1-1, after which the handle may be released, permitting the pressure switch 97 to return to open position. Energization of CR1 moves switches CR1-2, CR1-3, CR1-4, and CR1-5 into circuit closing position.

The control circuit itself is of conventional type in which the power leads 100 and 101 are connected to the primary 103 of a transformer having the secondary 104 with the leads 105 and 106. The several switch elements operated by each control relay have been set off for clarity by parentheses with the appropriate electrical conduits or leads extending outwardly from these parentheses when a switch controlled circuit is involved. In those instances, however, where the switch member or a lead connects directly to the transformer terminals 105 or 106, a dot indicating this connection and identified by the appropriate numeral 105 or 106 has been placed direct on the enclosing arm of the parentheses.

The machine grinding cycle

Assuming that the work piece 21 is in position between the headstock center 19 and tailstock center 20, the size control member 108 is moved into position for engagement with the work at diametrically opposite points by the anvil 109 and the movable plunger or feeler 110. It will be noted that

By reference to Figure 5, it will be noted that there have been provided a number of control valves in the hydraulic circuit including power cut-off valve 111 for cutting off supply of actuating medium to the motor 10, the rate selector

valve 112 for preventing return flow from the motor to the fast rate throttle valve 113 and thus to reservoir, and the rate control circuit bypass valve 141. Additionally, there is provided the solenoid actuatable valve 115 for control of the stop plunger 116, the solenoid operated valve 117 for control of the power cut-off valve 111 and the solenoid operated valve 118 for control of the rate valve 112. In Figure 5 the several valves have been shown with the machine stopped in retracted position. It will be noted that the valves 111 and 112 are held in shut-off position by the respective springs 119 and 120 and that the various solenoid operated valves 115, 117, and 118 are shown in their right hand positions as effected respectively by the springs 121, 122, and 123. As a result, the associated hydraulic controlled piston elements are coupled with the reservoir line 68. This prevents hydraulic operation of the various parts of the machine and insures automatic reversal or retraction of the wheel head under static conditions or in the event of failure or interruption of the electrical control circuit.

35 Alternatively, when the electrical control circuit is energized by movement of the control handle T in a counterclockwise direction, the several solenoids A, B, C, and D are energized, and the machine cycle is initiated. Movement of the valve 90 couples pressure conduit 65 through 124 and 125 and cannelure 126 of valve 127 with the rear of chamber 28 to react against piston 29 moving the same to the left as viewed in Figure 5. At the same time, conduit 128 from the left hand end of cylinder 24 is coupled by way of 89 and cannelure 92 to the return conduit 68. As piston 29 moves toward the left, dog 130 on rod 39 engages the collar 131 on valve 127, moving this valve to the left against the opening force of spring 132. Valve 127 has the taper or throttle portion 133 which tends to shut off the flow through port 144, reducing the supply of actuating medium to cylinder 28 so that as the port is closed, this medium is supplied only by way of choke coil 134 and groove 135, automatically reducing the rate of rapid traverse or initial infeed of the slide 22 which will then continue until the piston 29 is seated against the bed unit 45. The continuing pressure through coil 134 securely holds piston 29 forward against the fixed limit stop provided by the cylinder head locking the parts in position during the grinding operation. Pressure will then build up in 125 to open check valve 135 under pressure.

55 The actuating medium will then flow through check valve 135 and line 136 to valve 111. Actuation of solenoid B has moved valve 111 to the left, coupling 65 with 137 moving valve 111 downward, opening valve 138 to connect pressure conduit 136 to the intake side of motor 10, the exhaust from the motor going through 139. Pressure in 140 having moved return by-pass valve 141 to the left, the direct or unobstructed flow from motor exhaust line 139 to 68 is interrupted 60 and this flow is directed through 142. As solenoid C has been energized, valve 118 is then in its left hand position and pressure has flowed from 65 through 143 to move valve 112 downward. The return pressure flow therefore divides, part going by way of 144 through the fast feed rate valve 113 to low pressure or exhaust conduit 68 and part going by way of 145 and the fine feed rate valve 114. It will thus be seen 65 that the motor 10 is permitted to operate at a relatively rapid rate as determined by the joint

setting of the throttles 113 and 114. As pressure exists in conduits 86 due to setting of handle 85 and its associate valve in the "power" position, pinion 79 will have been shifted to the right so that the rotation of the motor will act through gear 43, pinion 36 and gear 35 to rotate screw 31 in a direction simultaneously to effect an advancing movement of the carriage 22 with respect to the piston rod 30. This operation will cause a clockwise movement of the gear 43 as viewed from the front of the machine, carrying with it the frictionally held compensator 41 which has been so positioned during set-up of the machine that the rotation of the pin or abutment 146 will engage and depress the cam surface 147 of rock arm 148 pivoted to the bed 15 as at 149. This arm is connected by link 150 with the limit switch LS2 which normally holds the member 146 in raised position with the cam 147 extending into the path of movement of 146. Depression of the link by arcuate movement of the pin 146 will operate LS2, closing a circuit to energize the timer 150. This is of conventional type which may be set as desired by adjustment of the indicator 151 for functioning for example in from one second to 120 seconds interval for effecting deenergization of the solenoid D so that valve 90 may shift and effect reverse or retracting movement of the wheel-head 22. The electrical control means, if desired, may be so coupled with LS2 that at the time of its actuation CR4 and thus solenoid C will be deenergized, allowing valve 112 to close. Closing of valve 112 shuts off the return flow from motor 70 by way of 142, 144, and the coarse or rapid feed throttle valve 113 to the low pressure return line 68. When this takes place the return flow can then only be through branch 145 and the fine or finish feed throttle 114, thus slowing down the rate of actuation of motor 70 and consequently the rate of rotation of feed screw 31. Alternatively, this deenergization of solenoid C may be placed under control of the gagging device plunger. As the work is reduced to its intermediate or coarse ground diameter, the movement of plunger 110 completes a circuit, permitting the control switch CR4-2 to open and deenergize solenoid C.

In the form of the invention shown in section in Figure 2, and in elevation, Figure 3, there has been shown as pivoted to the bed 15 a stop 154 urged into inoperative or disengaging position by plunger 155 actuated by spring 156.

For effecting counterclockwise movement of the stop to move its terminal abutment portion 157 into the arcuate path of movement of the member 146, there has been provided the plunger 116 coupled by conduit 158 with the valve 115. As previously described, during the initial portion of the cycle operation solenoid A is energized, holding valve 115 to the left so that its cannelle couples pressure line 65 through 158 to react on the piston plunger 116 and move the same downward, swinging the abutment 157 into operative position. When in this position, the abutment will contact and limit rotation of member 146 and thus of the frictionally driven compensatory member 41. In the initial set-up of the machine member 146 is preferably so adjusted as to just engage abutment 157 when the wheel head 22 has advanced the surface of the wheel to a point at which the rough or coarse grinding operation has been completed. Its movement, however, is absolutely a factor of the amount of feed rotation imparted to the screw 31 rather than a factor

of the actual position of the operative surface of the grinding wheel 23 which, as previously mentioned, may in effect recede due to wear, truing operations or the like.

This particular mechanism has, therefore, been provided to compensate for such wheel wear in order that the retraction and forward feed to limit of coarse grinding may be automatically maintained substantially constant as to distance, thus reducing the cycle time involved and the additional unnecessary retraction and forward advance of the grinding wheel accruing in the absence of such compensation.

If the change from coarse to fine feed is under control of the sizing device the limit of fast rotational movement of the gear 52 in a clockwise direction will be increased or advanced as the wheel surface is reduced since additional rotative movement must be imparted to the feed screw to make up for the wheel face recession. The contact between 146 and 157 will in effect cause a counterclockwise slippage of the member 52 and a clockwise slippage of the compensator drive 41 as respects the actual drive mechanism for the screw. As the members 52 and 49 are jointly meshed with the gear portion 48 of the member 41 this will cause a counterclockwise movement of the pin 158' which is carried by the member 49, moving it in a direction toward the cam surface 159 on rock arm 160 coupled by link 161 with the operating element of the limit switch LS1.

LS1 operates to deenergize solenoid B, coupling 137 to 68 as indicated in Figure 5, thus releasing valve 111 which moves to the blocking position also indicated in Figure 5, closing off the return line from motor 70 to stop its rotation and thus the extent of feed retraction of wheel head 22 effected by rotation of the screw 31. It will be evident that the closer pin 158' is to the point of actuating engagement for LS1 the shorter the amount of reverse feeding effected by the member 70, and consequently the shorter the forward feed movement to be effected by said motor during the grinding operation, or the less cutting of air during the operative portion of the feeding cycle. Since the reaction effect of stop 157 on pin 146 during the final feeding operation is to effect a counterclockwise movement of the pin 158' to compensate for any additional previous feed increment required to make up for wheel wear, it will be evident that the construction in question maintains a substantially constant back and forth feed stroke of the wheel head as effected by motor 70 to compensate for wheel wear and maintain the time of the grinding cycle substantially constant. This effect is, of course, dependent on the relative positional adjustment of the members 146 and 158'. To facilitate accurate positioning during setting up of the machine for a particular cycle the sleeve member 53 is preferably provided with the graduations 162 for cooperation with the pointer or index mark 163 on the member 61, these graduations therefore serving to indicate definitely the relative arcuate adjustment of the parts and being preferably marked in graduations corresponding to each .0001" diameter of the work.

It will be understood that in some instances, as for example, in manual operation of the machine that the automatic power feed control is not desirable. To lock out operation of motor 70 under these conditions the member 160 has been provided with the extension 164 overlying the piston plunger 165 mounted in cylinder 166 carried by the bed 15. Normally, this plunger is held in de-

its automatic position as before and switch 199 closed to complete the infeed control circuit, but switch 196 is adjusted to the "without gage" position shown in Figure 6.

The initiation of operation of the machine is as before in that closing of pressure switch PS5 energizes CR1 to initiate the machine cycle. In this instance, however, switch 196 has effected energization of control relay CR8, opening switch CR8-2 and closing switches CR8-1 and CR8-3, CR8-1 being connected to the timer TR1, to one side of LS2-2, to light LT3 and to control relay CR6. As the grinding proceeds, 146 will actuate LS2, activating the circuits just described to set the timer in operation and to energize CR6 and pilot light LT3. Opening of switch CR8-2 de-energizes control relay CR-3 and thus solenoid B, permitting valve 111 to move into position to stop the infeed motor 78. The parts will then dwell in the position established until operation of timer TR1 at the end of the prescribed selected interval closes TR1-1, picking up relay CR7, CR7-2 deenergizing CR2 and through CR2-5 solenoid D, effecting reverse or rapid retraction of the grinding wheel slide 22. Dropping out relay CR2 closes switch CR2-1, energizing CR3 and solenoid B, effecting reverse operation of feed screw 31 during the rapid retraction of slide 22 as previously described until CR3 is de-energized upon actuation of LS1 by pin 158. It will be noted that the compensator is equally effective in connection with this manner of operation but that the final grinding is effected as a sparking out rather than work size gaging operation.

By reference to Figure 6 it will be evident that moving switch 195 to break the upper blade "Auto" circuit will deenergize the control circuit by way of CR13-1, PS4-1, and in turn deenergizes CR-1. Closing the lower blade circuit "Size and True" of 195 energizes CR13 to hold open the control circuit at CR13-1.

Temporary deenergization of the control circuit for CR1 to drop out the circuits controlled by it and reverse and stop the machine cycle is effectable by opening PS4-1. This is accomplished by clockwise movement of lever T, coupling pressure from 65 to PS4 as indicated in Figure 5.

What is claimed is:

1. Control mechanism for a precision grinding machine of the type including a work support, and a grinding wheel support in which one of the supports is movable relative to the other for effecting the grinding operation, said control mechanism including a reversible hydraulic motor coupled with one of the supports for movement thereof, an auxiliary uni-directional hydraulic motor, reverser means intervening said second motor and the support for effecting supplemental movements of the support, and a hydraulic actuating system including a reversing valve and conduits intervening the reversing valve, said first hydraulic motor and said reverser and power couplable by the reversing valve, said conduits including a first conduit system couplable by the reversing valve for effecting one direction of actuation of the first motor and a corresponding actuation of the reverser, and additional conduits alternatively couplable by the reversing valve for effecting simultaneous opposite actuation of said first motor and said reverser.

2. Control mechanism for a precision grinding machine of the type including a work support, and a grinding wheel support in which one of

the supports is movable relative to the other for effecting the grinding operation, said control mechanism including a reversible hydraulic motor coupled with one of the supports for movement thereof, an auxiliary uni-directional hydraulic motor, reverser means intervening said second motor and the support for effecting supplemental movements of the support, and a hydraulic actuating system including a reversing valve and conduits intervening the reversing valve, said first hydraulic motor and said reverser and power couplable by the reversing valve, said conduits including a first conduit system couplable by the reversing valve for effecting one direction of actuation of the first motor and a corresponding actuation of the reverser, additional conduits alternatively couplable by the reversing valve for effecting simultaneous opposite actuation of said first motor and said reverser, and additional valve means intervening the reversing valve and the reverser mechanism for determining the effective coupling of the parts.

3. Control mechanism for a precision grinding machine of the type including a work support, and a grinding wheel support in which one of the supports is movable relative to the other for effecting the grinding operation, said control mechanism including a reversible hydraulic motor coupled with one of the supports for movement thereof, an auxiliary uni-directional hydraulic motor, reverser means intervening said second motor and the support for effecting supplemental movements of the support, and a hydraulic actuating system including a reversing valve and conduits intervening the reversing valve, said first hydraulic motor and said reverser and power couplable by the reversing valve, said conduits including a first conduit system couplable by the reversing valve for effecting one direction of actuation of the first motor and a corresponding actuation of the reverser, additional conduits alternatively couplable by the reversing valve for effecting simultaneous opposite actuation of said first motor and said reverser, a blocking valve in the hydraulic conduit system intervening the reversing valve and the unidirectional hydraulic motor for shutting off flow of actuating medium to the motor, and hydroelectric control means for determining the positioning of the blocking valve.

4. Control mechanism for a precision grinding machine of the type including a work support, and a grinding wheel support in which one of the supports is movable relative to the other for effecting the grinding operation, said control mechanism including a reversible hydraulic motor coupled with one of the supports for movement thereof, an auxiliary uni-directional hydraulic motor, reverser means intervening said second motor and the support for effecting supplemental movements of the support, and a hydraulic actuating system including a reversing valve and conduits intervening the reversing valve, said first hydraulic motor and said reverser and power couplable by the reversing valve, said conduits including a first conduit system couplable by the reversing valve for effecting one direction of actuation of the first motor and a corresponding actuation of the reverser, additional conduits alternatively couplable by the reversing valve for effecting simultaneous opposite actuation of said first motor and said reverser, a rate control mechanism for the unidirectional motor including a fast rate throttle valve, a slow rate throttle valve, a selector valve for determining the effective cou-

pressed position by the spring pressed plunger 167. Coupled with the cylinder 166, however, at the lower end is conduit 168 coupled with the selector valve as indicated in the section C—C. When the selector valve is in the left hand or manual control position 168 is connected with pressure line 65, raising plunger 165 and thus rocking lever 160 for actuation of LS1 to prevent energization of solenoid B for the motor release valve. When the selector lever is in its power position, 168 is connected to the reservoir conduit system 68 so that the plunger 165 will remain in the position indicated in Figure 3.

The electrical control system

The several electrical control relays, relay operated switches and circuits, together with associate parts have been diagrammatically illustrated in Figure 6. Reference has been made to utilization of the lever T to effect actuation of the pressure switch 97 temporarily to close switch PS5-1 to energize control relay CR1. For consideration of the automatic cycle of operation under gage control it is assumed that the "Auto" selector switch 195 has been manually closed, conditioning the machine for automatic operation and the selector switch 196 likewise closed for gage size control of the machine operation and the sizing gage placed in engagement with the work as shown in Figure 6, the unground work piece maintaining the switch blades 197 and 198 in raised position with reference to their respective control contacts 200 and 201. With the machine so conditioned, the circuit will be completed from 195 on CR2-4 by way of switch 195, normally closed switch CR13-1, PS4-1 and temporarily closed switch PS5-1, normally closed CR6-4 and CR7-3 to the operating solenoid CR1, closing the series of switches CR1-1 to CR1-5 operated thereby, the control relay being held energized through CR1-5. Closing of CR1-4 through normally closed CR7-2 energizes control relay CR2 which, in turn, through CR2-5 energizes solenoid D to effect forward rapid traverse movement of the grinding wheel while CR2 is locked by CR2-3. At the same time CR1-2 by way of closed selector switch 199 in its "Infeed" position and normally closed switch CR6-2 energizes CR3 which is then locked by CR3-2.

CR3-3 energizes solenoid B to shift valve 117 coupling pressure with conduit 137 to move valve 111 into open position, coupling actuating medium with motor 70 for actuation of feed screw 31 so that the wheel carrying slide or ram 22 is now being advanced toward the work both by the rapid traverse piston 29 and the action of motor 70.

CR3-1 through CR1-1 energizes CR5, which through CR5-3 activates solenoid A, moving valve 115 to couple pressure to 158, depressing 116 to move the compensator stop 157 upwardly as viewed in Figure 3 for engagement with pin 146. At the same time, CR5-1 by way of CR1-3 completes the circuit to energize CR4 and CR4-2 energizes solenoid C, shifting valve 118 to couple pressure through 143 moving valve 112 downward so that return conduit 142 from motor 70 is coupled with the rapid rate valve 113, permitting the more rapid operation of motor 70. The rapid traverse advance of slide 22 is terminated by engagement of piston 29 with the end of its cylinder so that continued feed is effected solely by motor 70. As motor 70 operates, pin 146 is moved in a clockwise direction, engaging the actuator 143 of limit switch LS2, actuation of this switch, opening switch LS2-1 and closing

LS2-2. Closing of LS2-2 initiates operation of the timer TR1 and activates the circuit to CR8-1, while interrupting one branch of the circuits from CR1-1 and CR5-2 to CR5. If there is no operation or too long a delayed operation of the gage control circuit, timer TR1 will function, interrupting the circuit through LS2 to stop the infeeding movement of the grinding wheel.

If, however, the machine is functioning in the normal manner by use of a suitable gaging mechanism, such as the two contact gage shown, for example, in Figure 6, the rapid feeding movement of the grinding wheel will cause a reduction in size of the work piece 21 until movement of plunger 110 closes the circuit from 196 through contact 202, energizing CR6 and signal light LT3. Energizing CR6 opens CR6-3, deenergizing the control circuit for CR4 which opens to the position shown in Figure 6, deenergizing solenoid C to release the retaining pressure against valve 112 which closes, as indicated in Figure 5, so that all subsequent exhaust flow from motor 70 must be through the slow feed rate valve 114.

Energization of CR6 opens CR6-1 and as LS2-1 has already been opened, this deenergizes CR5, opening CR10-3 to deenergize solenoid A, releasing the compensator stop 154 whose inner end is then depressed or swung downwardly by spring 156 out of the path of 146 so that member 146 may have an added incremental movement during the final fine feeding for finish grinding of the work piece 21.

As the work reaches final size, continued downward movement of the gage plunger 110 closes circuit through switch member 197 and contact 201 to CR1, opening the normally closed switches CR7-1, CR7-2, and CR7-3, controlling respectively the energization of CR4, CR2, and CR1.

Release of CR2-5 drops or deenergizes solenoid D, releasing valve 90 to reverse the fluid effect as respects piston 29 so that the wheel head slide 22 is rapidly retracted by pressure against the forward face of piston 25. At the same time, the pressure thus created in line 68, 89 meshes with gears 35, 78 for reverse rotation of the worm 31 as effected by the unidirectional operation of motor 70.

The retracting effect of motor 70 continues in its backing-off or counterclockwise actuation of the feed screw until the pin 158 through link 161 actuates LS1. Opening of LS1 by way of CR2-1 deenergizes control relay CR3, opening the circuit through CR3-3 to deenergize solenoid B, allowing the hydraulic stop valve 111 for supply line 136 to motor 70 to close, stopping the motor and thus screw 31 at a point determined by the compensatory effected positioning of the pin 158. It will thus be seen that a minimized retractive effect is produced by the motor 70 and that irrespective of the diameter or wearing away of the operative surface of the grinding wheel 23, due to the action of the gage and compensatory mechanism, a constant amount of rapid feed movement will be imparted to the grinding wheel in the production of successive work pieces. It is, of course, understood that the rearward retraction of the piston 29 continues to be effected by the pressure against piston 25 until the parts occupy the position shown in Figure 5 and the machine is conditioned for initiation of a new cycle of operation by movement of the starting handle T.

In the event that it is desired to perform an automatic cycle of operation without utilization of a work gaging device, switch 195 is placed in

13

pling of the fast rate throttle with the return conduit system, and a by-pass valve positionable to effect a direct coupling of the motor return conduit to exhaust.

5. Control mechanism for a precision grinding machine of the type including a work support, and a grinding wheel support in which one of the supports is movable relative to the other for effecting the grinding operation, said control mechanism including a reversible hydraulic motor coupled with one of the supports for movement thereof, an auxiliary uni-directional hydraulic motor, reverser means intervening said second motor and the support for effecting supplemental movements of the support, and a hydraulic actuating system including a reversing valve and conduits intervening the reversing valve, said first hydraulic motor and said reverser and power couplable by the reversing valve, said conduits including a first conduit system couplable by the reversing valve for effecting one direction of actuation of the first motor and a corresponding actuation of the reverser, additional conduits alternatively couplable by the reversing valve for effecting simultaneous opposite actuation of said first motor and said reverser, a rate control mechanism for the unidirectional motor including a fast rate throttle valve, a slow rate throttle valve, a selector valve for determining the effective coupling of the fast rate throttle with the return conduit system, a by-pass valve positionable to effect a direct coupling of the motor return conduit to exhaust, and control means for the by-pass valve including a conduit interconnecting the by-pass and reversing valves whereby shifting of the reversing valve couples pressure to determine the positioning of the by-pass valve.

6. A control mechanism for a grinding wheel slide including a feed screw, a hydraulic motor for actuation of the screw, drive gearing intervening the motor and screw including a mechanical reverser, a hydraulic control circuit for the reverser including a valve, and electrical control means for determining the positioning of the valve and thus the direction of actuation of the screw by the motor, said control means including a timing device and an actuator driven by the motor for setting said timing device.

7. A control mechanism for a grinding wheel slide including a feed screw, a hydraulic motor for actuation of the screw, drive gearing intervening the motor and screw including a mechanical reverser, a hydraulic control circuit for the reverser including a valve, electrical control means for determining the positioning of the valve and thus the direction of actuation of the screw by the motor, said control means including a timing device and an actuator driven by the motor for setting said timing device, an electric sizing device, and a control circuit intervening the sizing device and the electrical control for the valve for determination of the operation thereof.

8. A control mechanism for a grinding wheel slide including a feed screw, a hydraulic motor for actuation of the screw, drive gearing intervening the motor and screw including a mechanical reverser, a hydraulic control circuit for the reverser including a valve, electrical control means for determining the positioning of the valve and thus the direction of actuation of the screw by the motor, said control means including a timing device and an actuator driven by the motor for setting said timing device, an electric sizing device, a control circuit intervening

14

the sizing device and the electrical control for the valve for determination of the operation thereof, and selector means for determining the effective coupling of the sizing device with the control for the valve.

9. A precision grinding machine, including an advanceable and retractable wheel head supporting a grinding wheel, and an advanceable and retractable stop coupled with the wheel head for movement therewith and relative thereto, abutment means to engage and limit the advance movement of the stop to change its phase relationship with the wheel head to compensate for grinding wheel wear, said stop including independent abutment members respectively effective during advance and retraction of the wheel head, and means to adjust the phase relationship between said members.

10. In a precision grinding machine having an advanceable and retractable wheel head supporting a grinding wheel, wheel head drive means for imparting advance and retraction movements to the wheel head, a dog actuatable trip for limiting said retraction, a compensator including an abutment member effective during advancing movement of the wheel head and a dog movable therewith and effective to actuate the trip during retraction of the wheel head, a slip coupling between said compensator and the wheel head drive means, and means to limit the movement of the abutment to effect slippage of the compensator with respect to the wheel head drive.

11. In a precision grinding machine having an advanceable and retractable wheel head supporting a grinding wheel, wheel head drive means for imparting advance and retraction movements to the wheel head, a dog actuatable trip for limiting said retraction, a compensator including an abutment member effective during advancing movement of the wheel head and a dog movable therewith and effective to actuate the trip during retraction of the wheel head, a slip coupling between said compensator and the wheel head drive means, means to limit the movement of the abutment to effect slippage of the compensator with respect to the wheel head drive, and means to vary the effective spacing between the abutment and dog elements of the compensator.

12. Actuation and control means for the wheel head of a precision grinding machine, including a rapid traverse hydraulic motor and an auxiliary feed hydraulic motor, means connecting the respective motors to the wheel head for actuation thereof, a source of hydraulic actuating medium, and a control valve for the motors having a first operative position effective to couple the actuating medium to cause an advance movement of the rapid traverse motor and a coupling of the hydraulic medium to the feed motor, said valve having a second position effective to reverse the coupling to the rapid traverse motor while maintaining a power connection to the feed motor, and independent valve means intervening said valve and the feed motor for determining the operation of the feed motor.

13. Actuation and control means for the wheel head of a precision grinding machine, including a rapid traverse hydraulic motor and an auxiliary feed hydraulic motor, means connecting the respective motors to the wheel head for actuation thereof, a source of hydraulic actuating medium, and a control valve for the motors having a first operative position effective to couple the actuating medium to cause an advance movement of the rapid traverse motor and a cou-

pling of the hydraulic medium to the feed motor, said valve having a second position effective to reverse the coupling to the rapid traverse motor while maintaining a power connection to the feed motor, independent valve means intervening said valve and the feed motor for determining the operation of the feed motor, a mechanical reverser intervening the feed motor and the wheel head for determining the direction of actuation of the wheel head by the motor, and hydraulic conduits intervening said first valve and the reverser for coupling pressure thereto variably to position the reverser in accordance with the positioning of said first valve.

14. Actuation and control means for the wheel head of a precision grinding machine, including a rapid traverse hydraulic motor and an auxiliary feed hydraulic motor, means connecting the respective motors to the wheel head for actuation thereof, a source of hydraulic actuating medium, and a control valve for the motors having a first operative position effective to couple the actuating medium to cause an advance movement of the rapid traverse motor and a coupling of the hydraulic medium to the feed motor, said valve having a second position effective to reverse the coupling to the rapid traverse motor while maintaining a power connection to the feed motor, independent valve means intervening said valve and the feed motor for determining the operation of the feed motor, a mechanical reverser intervening the feed motor and the wheel head for determining the direction of actuation of the wheel head by the motor, hydraulic conduits intervening said first valve and the reverser for coupling pressure thereto variably to position the reverser in accordance with the positionings of said first valve, trip operable means for determining the position of the feed motor control valve, and a trip member movable with the wheel head for actuating said means to stop the operation of the feed motor.

15. Actuation and control means for the wheel head of a precision grinding machine, including a rapid traverse hydraulic motor and an auxiliary feed hydraulic motor, means connecting the respective motors to the wheel head for actuation thereof, a source of hydraulic actuating medium, and a control valve for the motors having a first operative position effective to couple the actuating medium to cause an advance movement of the rapid traverse motor and a coupling of the hydraulic medium to the feed motor, said valve having a second position effective to reverse the coupling to the rapid traverse motor while maintaining a power connection to the feed motor, independent valve means intervening said valve and the feed motor for determining the operation of the feed motor, a mechanical reverser intervening the feed motor and the wheel head for determining the direction of actuation of the wheel head by the motor, hydraulic conduits intervening said first valve and the reverser for coupling pressure thereto variably to position the reverser in accordance with the positionings of said first valve, trip operable means for determining the position of the feed motor control valve, a trip member movable with the wheel head for actuating said means to stop the operation of the feed motor, and an abutment engageable with the trip member upon advancing movement of the wheel head to effect a compensatory positioning of the trip member.

16. In a precision grinding machine having a translatable wheel head, means for effecting ad-

vancing and retracting movements of the wheel head including rotatable adjusting means, a motor for effecting rotation thereof, a trip operable stop device for determining the operation of the motor, and control means for said trip operable device including a pair of discs each provided with an abutment, a friction drive coupling the discs with the rotatable wheel head adjusting means to effect movement of the discs therewith while permitting controlled slippage of the discs with respect thereto, said drive including elements insuring synchronous rotation of the discs.

17. In a precision grinding machine having a translatable wheel head, means for effecting advancing and retracting movements of the wheel head including rotatable adjusting means, a motor for effecting rotation thereof, a trip operable stop device for determining the operation of the motor, control means for said trip operable device including a pair of discs each provided with an abutment, a friction drive coupling the discs with the rotatable wheel head adjusting means to effect movement of the discs therewith while permitting controlled slippage of the discs with respect thereto, said drive including elements insuring synchronous rotation of the discs, and means supporting the discs for relative movement whereby the phase relationship of the respective abutments on the discs may be varied.

18. In a precision grinding machine having a translatable wheel head, means for effecting advancing and retracting movements of the wheel head including rotatable adjusting means, a motor for effecting rotation thereof, a trip operable stop device for determining the operation of the motor, control means for said trip operable device including a pair of discs each provided with an abutment, a friction drive coupling the discs with the rotatable wheel head adjusting means to effect movement of the discs therewith while permitting controlled slippage of the discs with respect thereto, said drive including elements insuring synchronous rotation of the discs, means supporting the discs for relative movement whereby the phase relationship of the respective abutments on the discs may be varied, a retractable stop, and means to project the stop into the path of movement of the abutment on one of the discs to limit the movement of the discs with the wheel drive mechanism to vary the angular phase relationship of the discs with respect to the wheel drive mechanism.

19. In a precision grinding machine having a translatable wheel head, means for effecting advancing and retracting movements of the wheel head including rotatable adjusting means, a motor for effecting rotation thereof, a trip operable stop device for determining the operation of the motor, control means for said trip operable device including a pair of discs each provided with an abutment, a friction drive coupling the discs with the rotatable wheel head adjusting means to effect movement of the discs therewith while permitting controlled slippage of the discs with respect thereto, said drive including elements insuring synchronous rotation of the discs, means supporting the discs for relative movement whereby the phase relationship of the respective abutments on the discs may be varied, a retractable stop, means to project the stop into the path of movement of the abutment on one of the discs to limit the movement of the discs with the wheel drive mechanism to vary the angular phase relationship of the discs with respect to the wheel drive mechanism, a trip device actuatable by movement of one of said abutments, and means acti-

vated by said trip device for effecting retraction of the stop.

20. In a precision grinding machine having a translatable wheel head, means for effecting advancing and retracting movements of the wheel head including rotatable adjusting means, a motor for effecting rotation thereof, a trip operable stop device for determining the operation of the motor, control means for said trip operable device including a pair of discs each provided with an abutment, a friction drive coupling the discs with the rotatable wheel head adjusting means to effect movement of the discs therewith while permitting controlled slippage of the discs with respect thereto, said drive including elements insuring synchronous rotation of the discs, means supporting the discs for relative movement whereby the phase relationship of the respective abutments on the discs may be varied, a retractable stop, means to project the stop into the path of movement of the abutment on one of the discs to limit the movement of the discs with the wheel drive mechanism to vary the angular phase relationship of the discs with respect to the wheel drive mechanism, a trip device actuatable by movement of one of said abutments, means activated by said trip device for effecting retraction of the stop, a second trip device engageable by the other abutment during reverse movement of said abutment, and electric switch means coupled with said trip and operable thereby for controlling the operation of the feed motor.

21. In a precision grinding machine having a translatable wheel head, means for effecting advancing and retracting movements of the wheel head including rotatable adjusting means, a motor for effecting rotation thereof, a trip operable stop device for determining the operation of the motor, and control means for said trip operable device including a pair of discs, each provided with an abutment, a friction drive coupling the discs with the rotatable wheel head adjusting means to effect movement of the discs therewith while permitting controlled slippage of the discs with respect thereto, said drive including elements insuring synchronous rotation of the discs, a pair of trip members respectively engageable by the disc abutments during their forward and reverse movements, an electric circuit including a switch member and a timer device coupled with one of said trip members whereby engagement of the abutment and trip will effect movement of said switch, and a second control circuit including a switch and a feed motor stop valve control solenoid coupled with the other of said trip members and actuatable by the other disc abutment during the opposite direction of movement of the parts.

22. Actuation and control means for the wheel head slide of a precision grinding machine including a first slide actuating motor and an auxiliary slide actuating motor, a series of control valves for the respective motors including a direction determining valve for the first slide motor and independent rate and operation control valves for the auxiliary slide motor, means for biasing the valves in a position to move and hold the slide in retracted position, individually actuatable solenoids for controlling the movement of the several valves from their initially biased positions, and control means for said solenoids including an electric circuit embodying a reversing timer, a work sizing gage, serially arranged automatic cycle and infeed or traverse selector switches, and an additional selector switch for completing the

control circuits inclusive or exclusive of the sizing gage.

23. Actuation and control means for the wheel head slide of a precision grinding machine including a first slide actuating motor and an auxiliary slide actuating motor, a series of control valves for the respective motors including a direction determining valve for the first slide motor and independent rate and operation control valves for the auxiliary slide motor, means for biasing the valves in a position to move and hold the slide in retracted position, individually actuatable solenoids for controlling the movement of the several valves from their initially biased positions, and control means for said solenoids including an electric circuit embodying a reversing timer, a work sizing gage, serially arranged automatic cycle and infeed or traverse selector switches, an additional selector switch for completing the control circuits inclusive or exclusive of the sizing gage, and means for cyclically controlling the activation of the respective solenoids including control relays for the solenoids, a first limit switch having a portion operable in accordance with wheel head slide movements, a second limit switch having a portion activatable during wheel head retraction, and a series of control relays having operating circuits interruptable by activation of the limit switches for determining the cyclic deactivation of the valve controlling solenoids.

24. A precision grinding machine including a translatable wheel head, a motor for effecting advance and retracting movements of the wheel head at a feed rate, and means for automatically determining the extent of retraction of the wheel head including a wheel head retraction stop member movable in synchronism with the wheel head, a stop member presetting device including an interference abutment, a second abutment carried by the machine and projecting into the path of movement of the interference abutment as it is advanced in synchronism with the wheel head to limit the movement of said interference abutment, and means coupling the interference abutment and stop member whereby the effective positioning of said retraction stop member is automatically adjusted by limitation of the movement of the interference abutment during advancing movement of the wheel head.

25. A precision grinding machine including a wheel head supporting a grinding wheel, means for effecting an advance and a retraction stroke of the wheel head at a feed rate, an advanceable and retractable stop coupled with the wheel head advancing and retracting means for movement in synchronism therewith and for movement relative thereto, means operable by the stop to limit the amount of the retraction stroke of the wheel head, and an abutment carried by the machine in position to react against the stop and limit the advance movement of the stop to change its phased relationship with respect to the wheel head advancing and retracting means whereby to reduce the retraction stroke to compensate for reduction in wheel diameter.

26. A precision grinding machine including a wheel head supporting a grinding wheel, means for effecting an advance and retraction stroke of the wheel head at a feed rate, an advanceable and retractable retraction limiting stop frictionally coupled with the wheel head stroke effecting means for movement in synchronism therewith, the friction couple permitting relative movement between said means and said stop, means operable by the stop to limit the amount of retraction of

the wheel head, means to limit the advance movement of the stop only during synchronized advance movement of the stop and wheel head whereby to change the phase relationship between the stop and wheel head, said means including an abutment coupled with the stop, and a second stop carried by the machine for engagement with said abutment means to limit the advance movement of the retraction limiting stop, and additional presetable means to adjust the relationship between the abutment means and the retraction limiting stop to vary the length of stroke of the wheel head effected by the wheel head shifting means.

27. A precision grinding machine including a wheel head supporting a grinding wheel, means for effecting an advance and a retraction stroke of the wheel head at a feed rate, an advanceable and retractable stop coupled with the wheel head advancing and retracting means for movement in synchronism therewith and for movement relative thereto, means operable by the stop to limit the amount of the retraction stroke of the wheel

head, an abutment carried by the machine in position to react against the stop and limit the advance movement of the stop to change its phased relationship with respect to the wheel head advancing and retracting means whereby to reduce the retraction stroke to compensate for reduction in wheel diameter, and a work-engaging sizing device coupled with the wheel head stroke effecting means for effecting retraction of the wheel head and the retraction limiting stop.
